SPRING CONSTRUCTION

Andrew H. Ludwig, New York, N. Y.

Application December 9, 1942, Serial No. 468,420

7 Claims. (Cl. 267—1)

My invention relates to improvements in spring constructions which are adapted to operate at variable speeds by the adjustment of spring pressure means forming part thereof.

The object of my invention is to provide a device of this type carrying means by the adjustment of which its speed may be regulated between very slow and very fast limits, depending upon the particular purpose for which it is to be employed.

A further object of the invention is the provision of a device for securing spring action by the elimination of ordinary springs and the utilization instead of the material of which the members of the device are made.

Another object of the invention is the provision of a novel spring construction of great simplicity and economy of structure.

Other objects and advantages will appear from the description and the drawing forming part hereof.

In the embodiment of the invention shown herein, the device consists of a base to which are attached three spaced rods extending vertically therefrom, two of which are equipped with grooved bearings near their free ends. Detachably connected to these rods and movably held thereby is a substantially archlike frame. The extremities of the upper part of the frame are connected by a horizontal bar forming its lower part, and said horizontal part at its center is offset and provided with a grooved bearing.

The said archlike frame member is held in place on the said three vertical rods by positioning its horizontal bar so that the two end rods will bear against it on one side and the central rod against it on the other side.

Within the archlike frame and mounted between the horizontal bar forming its lower part and its upper portion are two jackscrews.

On the adjustment of the jackscrews to the desired tension, the horizontal bar is bowed or depressed along the central rod at the bearing in contact therewith, and on the downward and forward actuation of the archlike frame the said frame is caused to move at a substantially uniform speed until its upper part reaches a position slightly below the bearing on the offset portion of the horizontal bar, when, through the pressure of the end rods in one direction and the pressure of the center rod in the opposite direction co-operating with the bearing on the offset portion of the horizontal bar, which offset is now inclined upward, its action becomes either a quickened snappy spring motion or

one of slower speed, depending on the tension of the jackscrews.

It is obvious that its upward motion or actuation in reverse will be the same, the movement of the archlike frame member being substantially uniform until its part 5 reaches a position slightly above the bearing on the offset of the horizontal bar, when it will snap into vertical position or move more slowly to that position, depending on the tension at which the jackscrews have been set.

In the drawing,

Figure 1 is a front view of my device; and Fig. 2 a perspective thereof.

15 Similar letters of reference refer to corresponding parts.

Referring to the drawing, the base member of the device is designated 1. Fixedly attached to the base are three rods spaced from each other, 5 the central one of which is marked 2, the end rods being indicated by 3. Each of rods 3 is provided near its upper free end with a flanged grooved bearing 4.

20 Detachably and movably mounted on these rods is an archlike frame member consisting of an upper curved part 5, and a horizontal bar 6 connecting the extremities of said curved part. The center of the bar 6 is offset at 7, and said offset provided with a grooved bearing 8.

25 This frame member is mounted on rods 2 and 3 by placing the horizontal bar 6 in contact with the rear of the grooved bearings 4 on rods 3, as shown in Fig. 1, and the bearing 8 on offset 7 in contact with central rod 2, so that rod 30 2 will be positioned on the side of the bar 6 opposite the side against which rods 3 bear.

35 Arranged in spaced relation in the frame member between its bar 6 and upper part 5 are two jackscrews 9. These are so positioned on bar 6 that the upper end of each contacts the part 5 adjacent the ends of a bracing member 10.

40 From the foregoing, it will be clear that my invention consists of a very simple and effective spring construction, the jackscrews affording a 45 ready means of tensioning the device to the spring pressure desired for the required speed.

An advantageous feature of my device is that it provides means for take-up due to the wear on the bearings and fatigue in the spring tension rods caused by long use.

45 Certain modifications or changes may be made in the construction described without departing from the invention and the scope of the claims appended hereto. The central rod 2, for instance, could be extended back of the bracing member

when it is desired that the upper movement of the frame member abruptly cease in its vertical position. The shape or design of the archlike frame member may be varied. The bracing members could also be dispensed with, provided the upper part of the movable frame member were made strong enough to insure that the pressure from the jackscrews would have no effect on it but would always be exerted on horizontal bar 6.

It will be obvious, too, that offset 7 and bearing 8 may be varied to meet special requirements.

Aside from the base, my device is preferably made of spring steel and the part 5 adjacent its connection to horizontal bar 6 should be graduated to provide a certain amount of give on the depression of said bar to avoid possible breakage at the point of connection.

The device may be used in any type of apparatus in a part of which it is required to produce an intermittent or make-and-break action and in which it is necessary that such device have means for adjusting it to variable speeds to meet the particular requirements of the apparatus in which it is employed.

Among other uses, it is adapted to be employed as a very simple attachment for opening and closing a door and holding the door open or closed without the use of additional means. In such use the base 1, or its equivalent, with its three rods 2 and 3, is attached to the frame of the door on the hinge side thereof. The other part of the device, the arch 5 or its equivalent, is fastened to the door in any suitable way, so that it moves with and becomes part of the door in the same way as does one of the leaves of a hinge. It will be obvious that on opening of the door substantially half-way the pressure of the member 5, due to the adjustment of the jack screws, will cause the door to swing completely open and remain so without the use of a door check as is now necessary with the ordinary door closer. When it is desired to close the door the reverse action takes place, that is, on the movement of the door to substantially half-way of its closed position, the pressure of the member 5 operates to complete the closing of the door.

I claim:

1. The combination in a spring structure of the class described of two parts, one part adapted to be movably mounted on the other, one part comprising a plurality of spaced rods fixed to a support, and the other part comprising a member having a bar provided with an offset, and a grooved bearing in said offset, a rod in the first part adapted to seat against said offset bearing, the other rods having bearings adapted to contact the bar on its side opposite the side against which the rod in the offset bears, and screw means for exerting tension on said bar located between opposite parts of the member of which it forms a part.

2. The combination in a spring structure of the class described of two parts adjustable to each other, one part comprising a base and three rods attached to said base, two of the rods having grooved bearings, the other part comprising a member including a bar with an offset portion having a grooved bearing therein, one part of the spring structure adapted to be movably

mounted on its other part by placing said bar in the bearings on the two rods of the first-mentioned part so that the third rod will be on the side of the bar opposite the side against which the two spring rods bear, and will seat in the offset bearing on said bar, said bar adapted to respond to pressure exerted by tension means, said tension means consisting of jackscrews located between opposite parts of 10 the member of which the said bar forms a part.

3. In a spring structure, in combination, a base, a plurality of resilient rods extending therefrom, two of said rods provided with bearings, a member having parts spaced from each other, one part of which comprises a resilient bar having an offset portion, a bearing on said offset, the said member having spaced parts adapted to be movably mounted on said resilient rods by means of the bearings on the said offset and the said resilient rods, and screw means between the opposite parts of said member having spaced parts adapted to exert tension on the resilient bar forming part thereof.

4. In a spring structure, in combination, a base, a plurality of resilient rods extending therefrom, two of said rods having grooved bearings, a member one part of which comprises a resilient bar, said bar having an offset portion, a grooved bearing on said offset, screw means mounted between said resilient bar and the other part of 30 the member of which it forms a part, said last-mentioned member adapted to be held in position by the said grooved bearings, and, on the actuation of the device, to respond to the tensioning of the said resilient bar by the said screw means.

5. In a device of the class described, in combination, with three vertical spring steel rods and a base to which they are fixed, two of said 40 rods having grooved bearings thereon, of a member movably mounted on said rods, said member having a spring steel bar provided with an offset, and a bearing on said offset, and two jackscrews being mounted between said bar and the other part of the member of which the said bar forms a part, the said member mounted in position by placing its said bar in the bearing on said offset and the bearings on the other two rods, said member adapted to respond to the tensioning of the said bar by the said jackscrews.

6. In a spring structure, in combination, a base, three rods fixed thereto, two of the rods having grooved bearings near their free ends, a substantially archlike member, two jackscrews mounted therein, its lower part provided with an offset, a grooved bearing in said offset, said archlike member being movably mounted on said three rods by positioning its lower part in said grooved bearings, and adapted to be responsive to its tensioning by said jackscrews.

7. In a spring structure, in combination, a base, a plurality of rods fixed thereto, two of the rods having grooved bearings near their free ends, a member having jack screws mounted therein and provided with an offset, a grooved bearing in said offset, a third rod seated in said bearing near its free end, said member being adapted to co-operate with said rods and adapted to be responsive to its tensioning by said jack screws, substantially as described.

ANDREW H. LUDWIG.
